Primary Examiner — Antoine D Davis(74) *Attorney, Agent, or Firm* — Stephen R. Valancius(57) **CLAIM**

The ornamental design for a power tool attachment head, as shown and described.

DESCRIPTION

FIG. 1 is a perspective view of a power tool attachment head according to the present invention;
 FIG. 2 is a front view of the power tool attachment head of FIG. 1;
 FIG. 3 is a back view of the power tool attachment head of FIG. 1;
 FIG. 4 is a right side view of the power tool attachment head of FIG. 1;
 FIG. 5 is a left side view of the power tool attachment head of FIG. 1;
 FIG. 6 is a top view of the power tool attachment head of FIG. 1; and,
 FIG. 7 is a bottom view of the power tool attachment head of FIG. 1.
 The broken lines in the figures illustrate features that form no part of the claimed design.
